UNITED STATES PATENT OFFICE.

BURTNETT MCINTOSH, OF BROOKLYN, NEW YORK, ASSIGNEE, BY MESNE ASSIGNMENTS, TO FRANK A. HALL & SONS, A FIRM COMPOSED OF FRANK A. HALL, JR., AND HOWARD I. HALL, BOTH OF MONTCLAIR, NEW JERSEY, AND DWIGHT K. HALL, OF NEW YORK, N. Y.

DAVENPORT-BED.

1,367,067.

Specification of Letters Patent. Patented Feb. 1, 1921.

Application filed January 18, 1916. Serial No. 72,661.

To all whom it may concern:

Be it known that I, BURTNETT MCINTOSH, a citizen of the United States, residing at Brooklyn, in the county of Kings and State 5 of New York, have invented certain new and useful Improvements in Davenport-Beds, of which the following is a specification.

This invention relates to folding couches of the type sometimes called davenport beds.

10 In couches of this character it is usual to provide two telescoping or folding sections, which when extended form a full-sized bed upon which may be laid a mattress having a flexible central portion adapted to form a 15 fold. When such a couch is in the closed or folded condition, the mattress is folded in the center and the couch takes the form of a settee. Some couches of this type have many inherent disadvantages, one of which is that 20 when in the folded position there is no back rest, and when in the extended position the folded mattress, which is necessarily present, makes a poor bed, since the center fold allows parts of the spring to protrude so as to 25 make the couch anything but restful to the sleeper.

In the present invention I have aimed to provide a folding couch, which when in its folded condition affords a back-rest, fully 30 padded and substantially rigid and locked in position; and the seat portion (considering the couch in its folded condition), being also padded; so that if the couch be provided with a suitable cover it will have all the 35 appearance of a davenport.

A further aim of the present invention is to do away with the folding mattress, by making it in two distinct sections, one section being appropriated to each of the 40 movable parts of the device, the inner edges of the two sections, and of the mattress portions thereon, abutting against each other when the couch is extended, and preventing protrusion of any part of the spring.

45 Another object of the invention is to provide a construction of operating parts such that the device is easily manipulated to open or close the couch, and with the minimum exertion.

50 Still another object is to make the two sections of the device detachable, for compactness in shipping, &c.

Other objects and aims of the invention,

more or less broad than those stated, together with the advantages inherent, will be 55 in part obvious and in part specifically referred to in the course of the following description of the elements, combinations, arrangements of parts, and applications of principles constituting the invention; and 60 the scope of protection contemplated will appear from the claims.

In the accompanying drawings, which are to be taken as a part of this specification, and in which I have shown a merely preferred form of embodiment of the invention, Figure 1 is an end elevation of a couch embodying my invention, and showing the couch in the closed condition, in which it has the appearance of a davenport; Fig. 2 70 is a vertical detail section, on a large scale, taken on the line 2—2 of Fig. 1, looking in the direction of the arrows; Fig. 3 is an end elevation of the couch when in the open condition; Fig. 4 is a top plan view of the couch 75 when in the open condition, the mattress portions being broken away to reveal the parts beneath the same; Fig. 5 is a sectional view taken on the line 5—5 of Fig. 4 and looking in the direction of the arrows; Fig. 80 6 is a detail front elevation of the locking bar and associated parts; and Fig. 7 is a detail perspective view of one of the Y-shaped arms.

Referring to the numerals on the drawings, the couch is supported upon the floor by means of two end frames 10, connected together by means of longitudinal angle irons 11. The angle irons 11 are preferably connected by means of transverse angles 12. 90 The upwardly extending arms of the angles 12 are provided with detent notches 14 which are intended to be engaged by grooved wheels 52 that roll upon the track provided by this upwardly extending arm of each 95 angle 12, as hereinafter described. A back section 20 of the couch, and a seat section 40, are mounted between the two end frames 10, as illustrated in Fig. 1. A back section 20 is made up of an angle iron bent to form 100 a rectangular frame 21, the inner side of which is left open, but suitably braced by means of a tube 22 secured between the sides of the frame 21. This tube 22 is depressed below the level of the frame 21, and a suitable spring wire mesh 23 is secured to the 105

frame 21, upon which is supported a mattress portion 24 provided with strips 25 adapted to be secured with buttons 26 on the ends of the frame 21, as clearly shown in Fig. 1. At each end of the frame 21 there is a lug 27 secured thereto, and on the end of each lug 27 there is a headed rivet 28 engaging in a keyhole slot 29 formed in the end of a link 30, the other end of each link 30 being mounted on a pivot 31 secured in the respective end frames 10. (See Figs. 1 and 3). It will be understood that similar parts are provided at each end of the device, although the description is confined to the set of parts shown at one end in Figs. 1 and 3. Also secured to the ends of the frame 21 are lugs 32 located adjacent to the inner corners of said frame, these lugs 32 being provided with pivot screws 33, the purpose of which will be hereinafter referred to.

The forward or seat section 40 is made up of a framework consisting of end angles 41 and longitudinal tubes 42 and 43. The tube 42 is located to the rear or inner side of the section 40, and is secured at each end to fittings 44, which in turn are each secured to one end of the respective angles 41. The tube 43 is located at the front of the section 40 and is secured at each end to fittings 50 which are respectively secured to the other ends of the two angles 41. Each fitting 50 is secured to a leg 51 depending from the section 50, and on the end of each leg 51 is a caster 52 adapted to roll on the floor, these legs 51 supporting the front of the section 40 so that it will be on a level with the section 20 in the Fig. 3 or extended position. Each fitting 44 consists of a vertically disposed plate 45, the top of which is bent at right angles to form an outwardly extending lug 46. On the inner side of the plate 45, and integral therewith, there is a boss 47, in which the end of the longitudinal tube 42 is secured. Above this boss 47 the end of the angle iron 41 is suitably secured to the plate 45, as by brazing or otherwise. A spring mesh 48 is secured between the angle irons 41, and a mattress portion 49 is supported upon the section 40, as shown in Figs. 1, 3, 4 and 5. As before stated, the front of the seat section 40 is supported on the legs 51 which rest on the floor, and the rear of the seat section 40 is supported by means of grooved wheels 52 which are adapted to roll on the transverse angles 12 and the main frame. These grooved wheels 52 are mounted in U-shaped brackets 53 secured to the fittings 44 as by means of screws 54, the brackets 53 being so bent that a space 55 is left between them and the plate 45 of the fitting 44, and a shoulder 55' thereby established is adapted to support bar 58 when the couch is in the closed condition

(see Figs. 1 and 2). The back section 20 is suspended from the main frame by means of the links 30 and the lugs 27 heretofore described. Means for holding this back section 20 rigid, so that it cannot rock on the pivots 28, are provided, as follows: Adjacent to the front corners of the end angles 41 of the seat section 40 are secured upwardly extending lugs 56, to which are pivoted, on pins 57, flat bars 58, the other end of each bar 58 being pivoted to the lugs 32 on the back section 20, as indicated at 33. A coiled spring 59 extends between a lug 60 on each fitting 50 and each bar 58, the tendency of this spring 59 being to pull its bar 58 downwardly.

Projecting from the side of each bar 58 is a pin 61 adapted to engage in a slot 63 formed in a Y-shaped arm 62, the latter being pivoted as at 67 to a lug 68 secured to one of the longitudinal angle irons 11 which make up the main frame or body of the couch. Referring to Fig. 7, it will be seen that the arm 62 is substantially a flat plate in the general form of a small letter Y, its upper edge being indented with a vertical slot 63, while from each of the corners extend lugs 64 and 65, connected by a web 66. The bar 58 is adapted to lie between the surface of the arm 62 proper and the web 66, with the lower edge of the bar resting on the lug 65, while the upper edge is under the lug 64, as shown in Fig. 3.

From the foregoing description it is evident that the back section 20 cannot roll on the pivots 28 when in the open position shown in Fig. 3, because each bar 58 being secured to its lug 32 of the frame 31, and said bar resting on the lug 65 of the Y-shaped arm 62, the inner side of the section 20 cannot be rocked downwardly; and likewise since the upper edge of each bar 58 is under its appropriate lug 46 of fitting 44, it cannot be rocked upwardly, and accordingly remains rigid in the Fig. 3 position. In this position it will be noted that the Y-shaped arm 62 has been swung to such an angle that the lug 65 is slightly beyond the pivotal support 68 thereby effectively locking the bar 58 against downward movement until the said arm 62 has been moved inward due to the pin 61 within the slot 63 to such an extent as to move the lug 65 to the other side of the pivotal support 68.

Means for locking the couch in the open and closed positions are shown, as follows. A transverse bar 70, having upwardly turned ends 71, is mounted on a pivot 72 in the longitudinal tube 42 at the inner side of the section 40, and on a pivot 73 in the longitudinal tube 43 at the forward side of the section 40. Bar 70 is provided with notches 74 and 75 (see Fig. 4), adapted to engage lug 76 secured to the forward longitudinal angles

11 of the stationary frame of the couch. Bar 70 is adapted to be rocked on its pivots 72 and 73, as indicated by full and dotted lines in Fig. 6, but normally it hangs in the full line position of Fig. 6, by gravity, and when in the open position shown in Figs. 3, 4 and 5, the notch 74 is in engagement with the lug 76, which prevents the seat section 40 from being pushed in until the bar 70 is 10 rocked out of engagement with the lug 76, as shown by the dotted lines in Fig. 6. When the couch is in the closed position shown in Fig. 1, the notch 75 on the bar 70 is in engagement with the lug 76, and the seat section 40 cannot be pulled out until the bar 70 is rocked out of such engagement.

The operation of the couch, beginning with the open position shown in Fig. 3, may be described as follows. To close the couch 20 it is first necessary to rock the bar 70 on its pivots 72 and 73, so as to disengage the notch 74 from the lug 76. A slight push against the seat section 40, assisted by the springs 59, causes the bars 58 to drop down just far enough to break the substantially straight line between the pivots 57, 33 and 28. This causes the inner side of the back section 20 to move downwardly. It cannot swing up because the bars 58 are in contact with the 25 lugs 46 on the fittings 44. It could not swing downwardly if the initial push were not given, because the bars 58 are resting above the lugs 65 on the Y-shaped arms 62, but as this initial push is applied the pins 35 61 engaging in the slots 63 in the arms 62 causes the rocking of the arms 62 on the pivots 67, and as the seat section 40 begins to roll on its casters 52 and the grooved wheels 53, the back section 20 also begins to 40 swing on the pivots 28, until each bar 58 has dropped to a position where it rests on the shoulder 55' at the bottom of the space 55 between the plate 45 and the U-bracket 53. From this point on until the maximum 45 closed position shown in Fig. 1 is reached, the back section 20 turns on the pivot 31 of the link 30, and when this closed position is reached the notch 75 on the bar 70 falls by gravity into engagement with the lug 76 50 and thus locks the couch in the closed position.

It will be noted that the pin 61 on the bar 58 has now passed out of the slot 63 in the Y-shaped arm 62, but this slot is held in 55 proper position to engage the pin 61 when the couch is to be opened, by means of the lug 64 on the Y-shaped arm 62 resting on the upper edge of the bar 58.

When necessary to ship the couch, the 60 pivot screws 33 may be removed, and the back section 20 raised so as to disengage the headed rivets 28 from the keyhole slots 29 in the links 30. The back section 20 may then be laid on top of the seat section 40,

thus providing a regularly shaped article 65 which is easily crated.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense. 75

It is also to be understood that the language used in the following claims is intended to cover all the generic and specific features of the invention herein described and all statements of the scope of the invention, which, as a matter of language, might be said to fall therebetween. 80

I claim:

1. In a device of the kind described, a supporting frame, a back section pivotally secured thereto and adapted to assume either a vertical or a horizontal position, a track forming a part of the main frame, a front section slideable on said track and connected to said back section, and a gravity lock for 90 maintaining the slideable section in either one of two positions, said lock constituting a co-operating lug and pivoted notched bar. 85

2. In a davenport bed, comprising side arm portions constituting supporting frames, a back section pivotally secured thereto and adapted to be moved to either one of two positions, a front section movable horizontally upon the frame, a connection between the sections to move them together, a lug secured to the frame, and a pivoted notched bar carried by the front section, said bar arranged to co-operate with said lug to lock the front section in either one of two positions. 95

3. In a davenport bed, comprising side arm portions constituting supporting frames, a back section pivotally secured thereto and adapted to be moved to either a horizontal or a vertical position, a front section slideable in a horizontal position with respect to the frame, a link connection between the said sections and means co-operating with said link connection to prevent upward or downward movement of the same 110 until the front section is positively moved. 115

4. In a davenport bed, comprising side arm portions constituting supporting frames, a back section pivotally secured thereto and adapted to be moved to either a horizontal or a vertical position, a front section slideable in a horizontal position with respect to the frame, a link connection between the said sections, a member pivotally secured to the frame and adapted to co-operate with said link connection to prevent a downward movement of the same until the front section is positively moved. 120 125

5. In a davenport bed, comprising side arm portions constituting supporting frames, a back section pivotally secured thereto and adapted to be moved to either a horizontal or a vertical position, a front section slideable in a horizontal position with respect to the frame, a link connection between the said sections, a lug associated with the front section, and a pivoted mem-

ber secured to the supporting frame, said 10 lug and pivoted member adapted to co-operate with the link connection to prevent upward or downward movement of the same until the front section is positively moved. 15

In testimony whereof I affix my signature.

BURTNELL MCINTOSH.
